UNITED STATES PATENT OFFICE

CLAYTON G. WILCOX AND JEREMIAH J. SHOEMAKER, OF GARRETTSVILLE, OHIO

TRAFFIC LIGHT

Application filed December 17, 1930. Serial No. 502,949.

This invention relates to traffic signal devices, employed at the junction of streets where vehicles of different kinds cross each others' path, and has for one of its objects to provide an electrically actuated apparatus whereby signals may be displayed to the view of the drivers of vehicles approaching from a plurality of directions, and including light bulbs of different colors and means for changing the illuminating means at predetermined intervals.

With the above and other objects in view, the invention consists substantially in the structure herein shown, described and defined in the claims, and in the drawings illustrative of the preferred embodiment of the invention in which:

Figure 1 is a vertical section viewed from one side.

Figure 2 is a vertical section viewed at right angles to Fig. 1.

Figure 3 is a transverse section on the line 3—3 of Fig. 1.

Figure 4 is a diagram of the electric wiring.

The improved apparatus includes an enclosing shell or casing 10 preferably polygonal in cross section, and having openings 11 in one or more sides. Supported within the openings are glass or transparent panels 12 through which the light imparting means is observable. Disposed within the shell 10 is a bracket or standard 13 having a lateral extension 14 carrying bearings 15 and 16 to support centrally thereof a vertical shaft 17. At its upper end the shaft 17 is formed with a plurality of lateral branches 18 upturned at their outer ends and each terminating in a bearing 19 carrying a laterally directed stub shaft 20, each of the stub shafts carrying a bevel gear 21. The shaft 17 also carries a bevel gear 22 meshing with all of the bevel gears 21 whereby motion is transmitted from the vertical shaft 17 simultaneously to all of the stub shafts through the gears 21.

Attached to the outer ends of each of the

stub shafts 20 and rotative therewith and within the casing, is a radially directed frame 24 which may well be rectangular in outline and having a transparent member 25 of different color inserted therein. The frame 50 being closely adjacent the panel 12, is rotatably movable in a plane parallel to such panel. Coupled, fixedly to each of the stationary bearings 19 is a concave reflecting mirror 26, the same being spaced from the 55 casing wall so that the frame 24 may move between the panel and mirror.

The source of light is within the mirror and between the latter and frame, as will be later explained.

The main drive shaft is indicated at 27, and is adapted to be driven by a suitable motor (not shown) and carries a bevel gear 28 on the inner end in engagement with a bevel gear 29 on the shaft 17. The shaft 17 is supported by a stop collar 30, and continuing the shaft 17 downwardly is a separate section 31. The shaft 17 carries a clutch member 32, while the shaft section 31 carries an opposing clutch member 33. Slidable on the shaft section 31 between the clutch members 32 and 33 is a double-faced clutch member 34 adapted to be alternately engaged with the clutch members 32 and 33. A collar 35 encircles a sleeve 35' on the shaft section 31 70 and supports the inner end of the drive shaft 27.

Mounted to swing at 36 to the standard 13 is a shipper lever 37, the free end of the lever being coupled in the usual manner to operate the double-faced clutch member 34. A solenoid magnet, indicated at 38, is coupled by its core rod 39 to the shipper lever 37, the solenoid being adapted to operate the shipper lever and thus control the movements of the 75 clutches.

Supported by a standard 40 within the casing 10 is a rotative non-conductive drum 41 carrying alternating contacts 42—43—44 with which spring contacts 45—46—47 are 80

adapted to be alternately engaged to make and break contacts as the drum is rotated. The shaft of the drum 41 carried a bevel wheel 48 engaging a bevel pinion 49 on the 5 shaft section 31. By this means the rotation of the shaft 31 is communicated to the drum 41.

One or more light bulbs, indicated at 50, are fixedly disposed within each of the reflectors 26, and sufficiently spaced from the 10 casing wall to be out of the path movement of the frame 24.

The shaft section 31 is provided with a bevel gear 51 engaging a smaller bevel gear 15 52 formed on the larger gear 28 by which motion is communicated to the shaft 31 and its connections.

Having now described our invention, that 20 which we claim to be new and desire to secure by Letters Patent is:

1. In an apparatus of the class described, a stationary light transmitting medium, a stationary reflector associated with said medium, a member movable transversely of 25 said medium and about the axis of said reflector, and having a transparent portion through which the light rays from said medium and reflector pass.

2. In an apparatus of the class described 30 including an enclosing casing having a plurality of lateral openings and a vertical shaft having a drive gear centrally mounted within said casing, a plurality of stub shafts associated with said vertical shaft, directed toward 35 the several openings and respectively carrying gears meshing with the gear of the vertical shaft, a member within said casing carried by each of the said stub shafts and rotative therewith, and each having a trans- 40 parent portion, a light transmitting medium from which light passes through said transparent portions and lateral openings, and means for imparting motion to said drive shaft and the parts connected therewith.

45 3. In an apparatus of the class described, an enclosing casing having a lateral opening, a rotatable drive shaft mounted within said casing, a stub shaft, means for transmitting motion from the drive shaft to the stub shaft, 50 a member rotative with said stub shaft and having a transparent portion moving in a plane parallel with said opening, and a light medium within said casing adapted to transmit its rays through said transparent portion 55 and lateral opening.

4. In an apparatus of the class described, 60 a casing having a plurality of spaced lateral openings, a vertical shaft centrally mounted within said casing and having a drive gear on its upper end, a plurality of stub shafts directed toward the several openings and respectively carrying gears meshing with the gear of the vertical shaft, a stationary reflecting mirror adjacent each of said openings and concentric with a stub shaft, a light

transmitting medium fixed relative to each of said mirrors and mounted between the same and the openings, a member rotative with each of said stub shafts and having a transparent portion and having a path of movement in a plane between said opening and mirror and coaxial with the latter, and means for actuating said vertical shaft.

In testimony whereof we affix our signatures.

CLAYTON G. WILCOX.

JEREMIAH J. SHOEMAKER.
